[57] CLAIM

The ornamental design for a combined string reel and light bulb storage compartment, as shown and described.

DESCRIPTION

FIG. 1 is a perspective view of a combined string reel and light bulb storage compartment showing my new design with the bulb storage lid opened;

FIG. 2 is a top plan view thereof;

FIG. 3 is a rear elevational view thereof;

FIG. 4 is a bottom plan view thereof;

FIG. 5 is a front elevational view thereof; and,

FIG. 6 is a side elevational view thereof with the opposite side being a mirror image thereof.

FIG.1.

FIG.2.

FIG.3.

FIG. 4.

FIG. 5.

FIG. 6.
